UNITED STATES PATENT OFFICE

HAROLD B. HAWES, OF FAIRFIELD, CONNECTICUT, ASSIGNOR TO G. DROUVE CO., OF FAIRFIELD, CONNECTICUT, A CORPORATION OF CONNECTICUT

GLASS STRUCTURE

Application filed September 12, 1930. Serial No. 481,368.

My invention has reference to glass structures, but refers specifically to an improvement in the structure shown and described in Letters Patent No. 1,632,380, issued to me ⁵ June 14, 1927, and consists of an improved way of assembling and securing what is termed in said patent the "elongated gutter section 6".

The object of this invention is to not only ¹⁰ more readily assemble this section and the rafter bar, but also to render them easily detachable from the rest of the structure, and furthermore to effectually prevent moisture from seeping down below said gutter section.

¹⁵ In order that the invention may be more clearly understood I have illustrated in the drawings the general structure shown and described in said Letters Patent, but will merely refer to certain parts by numerals of reference without entering into details regarding them, since their construction and function are the same as described in said patent.

Referring to the drawings—

Figure 1 is a broken perspective view of ²⁵ a unit of a skylight structure embodying this invention—

Figure 2 is a cross-section taken at any point intermediate the rafter bar clips with all parts assembled—

³⁰ Figure 3 is a cross-section with certain parts in position for assembly, and particularly showing the air circulating spaces between the rafter bar and condensation gutter and between the latter and the glass rest, this ³⁵ section demonstrating particularly that, at all locations intermediate the rafter carrying clips, there is a free circulation of air—

Figure 4 is a cross-section similar to Figure 2, but illustrating a way of strengthening the rafter bar instead of substituting a wider one—

Figure 5 is a detail perspective view of the elongated gutter equipped for ready attachment to the rafter bar—

⁴⁵ Figure 6 is a detail perspective view of the rafter bar with spaced clips welded thereto and constructed to receive the rafter bar, and

⁵⁰ Figure 7 is a section at the line 7—7 of Figure 2.

Similar numerals of reference denote like parts in the several figures of the drawings.

The drawings illustrate only a part of a skylight unit, but it must be understood that there are many of these units each one of ⁵⁵ which has its rafter bar secured at spaced locations to certain clips, and the sectional structures shown in the drawings can be duplicated many times throughout the length of a rafter bar.

⁶⁰ 1 is the rafter bar, and 2 are sheet metal clips which embrace said bar at spaced locations and are welded thereto, and the top portions 3 of these clips are flat and are spaced from the upper edge of said bar for the purpose presently explained.

⁶⁵ In corresponding edges of these portions 3 are open gates 4 to facilitate the attachment of the elongated gutter 5 which is parallel to said bar, through which gutter from the bottom of its middle at spaced locations and preparatory to assembly extend screws or bolts 6 with nuts 7 driven thereon above and against the gutter.

⁷⁰ In assembling and securing this gutter, the nuts 7 are backed so as to permit the heads 8 of the bolts 6 to be spaced from the gutter as shown at Figure 5 a distance sufficient to allow the portions 3 to be entered beneath the gutter with the gates 4 embracing the ⁷⁵ bolts as shown at Figure 7 so that the gutter will be intermediate the nuts 7 and the heads 8 of the bolts, and the nuts are then tightened so that the gutter will be firmly held at spaced locations between these nuts and heads, there- ⁸⁰ by not only providing a simple and firm construction, but sealing the gutter above and below as against moisture seeping.

⁸⁵ The glass support 9 with superimposed asphaltic cushion 10, and glass sections 11 ⁹⁰ with superimposed asphaltic cushion 12, are all assembled as is shown in said Letters Patent, and the bolts 6 extend upwardly through these parts and through a cap 14 that rests on the cushion 12, and binding nuts 15 are driven ⁹⁵ on the ends of these bolts against said cap to force the latter firmly against the cushion 12 and bind all parts securely together, likewise as shown in said patent.

¹⁰⁰ The construction of rafter bars shown at

Figure 4, and denoted by the numeral 16 is T-shaped at its bottom edge to afford greater strength in the event that the length of the span and the weight to be supported thereby 5 are greater than usual, and it will be clearly evident that, in instances of this sort, the present invention renders the substitution of one kind of rafter for another already installed a comparatively simple matter.

10 It will be evident that there is a free circulation of air between the glass support 9 and gutters 5, between the rafter bars throughout the major portion of their lengths and glass support 9, and between the rafter 15 bars and the gutters throughout their entire lengths owing to the spacing between the top portions of the clip 2 and said bars, and therefore the likelihood of any moisture condensing on said bars and outer faces of said gutters is reduced to a minimum, and all other 20 condensation will drip into the gutters and be disposed of in the usual manner.

While it is preferred to mount the glass sections as shown in the drawings, employing 25 a separate glass support member, a fibrous washer and a gutter, it will be clear that the entire superstructure is supported by the clips and rafter bar, and therefore any suitable parts may be assembled on the clips to 30 hold the glass sections, so long as the gutters and clips are assembled and secured together in the manner described and the bolts and nuts utilized to secure all parts firmly together, and therefore the invention is not limited 35 in these respects.

What is claimed is:

1. In a glass structure unit as described, 40 having a rafter bar, a series of sheet metal clips welded to said bar at different locations and having flat upper portions spaced from said bar and having open gates, an elongated gutter resting upon and embracing said clips, bolts passed through said clips and gutter and extending upwardly, nuts driven on said 45 bolts against the gutter whereby the latter is secured to the clips between the bolt heads and said nuts.

2. A unit for a glass structure as described, 50 having a rafter bar, a series of sheet metal clips welded to said bar at spaced locations and having level upper portions that are spaced from said bar and provided with corresponding open gates, and an elongated gutter supported by and embracing said clips, bolts carried by said gutter and adapted to 55 enter said gates, and nuts driven on said bolts against said gutter whereby said rafter bar and gutter are secured together as a separate unit.

60 3. In a glass structure unit as described, having a rafter bar, a series of sheet metal clips welded to said bar at desired locations and having flat upper faces spaced from said bar and formed with gates, an elongated 65 gutter parallel with said bar and embracing

said clips, bolts passed through said gates and gutter and extending upwardly, a cap through which the free ends of said bolts extend, nuts on said bolts above said gutter whereby the latter is secured to said clips, and glass sections and associated parts supported by said clips intermediate the latter and said cap, and nuts driven on the ends of the bolts against the caps.

4. A unit for a glass structure as described, 70 having a rafter bar, a series of clips whose lower portions embrace said bar and are welded thereto at spaced locations and whose upper portions are flat and spaced from said bar and formed with corresponding open gates, an elongated gutter supported by said upper portions and embracing the clips, bolts extending from the inside of said upper portions through said gates and gutter, and nuts driven on said bolts against said gutter, whereby the latter and said rafter bar are detachably secured together.

In testimony whereof I affix my signature hereto.

HAROLD B. HAWES.
